UNITED STATES PATENT OFFICE.

LEON F. DOUGLASS, OF SAN RAFAEL, CALIFORNIA, ASSIGNOR TO VICTOR TALKING MACHINE COMPANY, A CORPORATION OF NEW JERSEY.

SOUND-REPRODUCING MACHINE.

Application filed April 24, 1916, Serial No. 93,275. Renewed April 27, 1922. Serial No. 557,035.

To all whom it may concern:

Be it known that I, LEON F. DOUGLASS, a citizen of the United States, residing at San Rafael, county of Marin, and State of California, have invented certain new and useful Improvements in Sound-Reproducing Machines, of which the following is a specification, reference being had to the accompanying drawings, forming a part thereof.

My invention relates to sound reproducing machines comprising any well known form of reproducer including a vibratable diaphragm and stylus to actuate it, with means to receive and amplify the sound waves created thereby and discharge them to the atmosphere, and my invented improvements have for their primary object the utilization of such sound waves to cause variations corresponding to sound waves in an electric circuit and transform said vibrations in said electric circuit back into secondary sound vibrations, whereby the primary vibrations produced by such diaphragm are caused to produce a secondary reproduction of recorded sound vibrations and through amplifying passages as desired; and additionally whereby the secondary vibrations may be varied, that is to say, the volume of the sound ultimately delivered can be made greater or less, as desired. Both sets of vibrations are provided for by mechanism which is enclosed within a single cabinet so that the manipulation of the secondary vibrations for the purpose of enhancing the primary vibrations is readily controlled.

To these ends my invention, while it does not broadly comprehend the reception upon a telephone circuit, of the sound vibrations emanating from a talking machine, as that is not new, it involves that basic principle, exemplified in mechanism so combining, in a novel manner, the diaphragm holder or sound box of a sound reproducing machine, its tone arm, and, if desired, its horn or other mechanical amplifier of sound waves, with telephonic receiving and discharging apparatus, whereby each or all of the desired results, above stated, are produced. The term secondary reproduction, in the sense in which I use it, means the electrically-created sound pulsations of the diaphragm of the telephone apparatus, as distinguished from the diaphragm of the

sound box of the talking machine which produces the sound waves constituting what I refer to as the primary vibrations.

The defect in the known method and means of exemplifying the basic principle referred to, is largely due to connecting the telephone circuit directly to the stylus of the diaphragm holder forming part of the usual sound box of the talking machine or to the diaphragm thereof, which results in weighing the stylus or diaphragm, or otherwise decreasing the effectiveness of such diaphragm, by noticeably lessening the volume of the sound produced thereby and frequently varying its tone and timbre. This defect is entirely overcome in my device wherein the diaphragm is free from such connection and the effectiveness of the primary vibrations is retained, the resultant secondary vibrations conveyed to relatively distant points, and wherein moreover the secondary vibrations are or may be augmented in volume by the means hereinafter described.

In the accompanying drawings illustrating the best form in which I have embodied my invention:

Figure 1 is a vertical section, partly in elevation, through the vertical center of the apparatus shown mounted in a duplex containing casing;

Fig. 2 is a plan view, partly in section, of a known form of tone arm construction, with sound box or diaphragm holder, and showing the telephone transmitter and circuit connections mounted upon the articulated extremity of the tone arm proper;

Fig. 3 is a central section, partly in elevation, of the receiver of a telephonic apparatus mounted dependently on the inlet-end of a vertically disposed amplifying device;

Fig. 4 is a section on line 4—4 of Fig. 2 of a perforated plug through which primary sound vibrations pass from the tone arm of the machine to the transmitter of the telephone circuit.

Referring now to said drawings, 1 and 21 indicate, respectively, the two members of a duplex containing cabinet, of which 1 is of known form and character, within which are operatively mounted, in a known way, the horizontally swinging tone arm 3 of a sound reproducing apparatus, with a known character of sound box or diaphragm and stylus

holder 2 mounted on the free end of the tone arm; a rotatable record holder 23 and a motor 24^a to operate it. Extending downwardly through a lower chamber in the cabinet member 1 is a tubular conduit 25 operatively connected with the open swivelled end of the tone arm 3, and serving as a passage way and conduit for the primary sound vibrations created by the diaphragm of the sound box 2.

Rearward of the cabinet member 1 is mounted a second cabinet member 21, with coinciding apertures 26 and 27 between the contiguous walls of the two cabinet members. Through the lower of these apertures, 26, extends the aforesaid sound wave conduit 25 which, when it enters the cabinet member 21 is reversely curved to extend upwardly as at 25^a for a short distance, preferably in conical formation, and thereafter may extend integrally to the open top of the cabinet member, operating in the usual manner as an amplifying tube or horn, or it may support mounted therein, as shown in Fig. 1, a conical or flaring rectangular amplifying chamber 21^a, containing, if desired, one or a series of partitioning and vertically disposed sounding boards 21^b. A hinged lid 22^a may be supplied for the supplemental cabinet member 21, or for both. A duplicate amplifying chamber 20 or its equivalent referred to, is also mounted in the cabinet member 21, the basal or inlet end of the member 20 being operatively connected to the larger end of a preferably tapered sound tube 20^a mounted on standards 20^b; the lower end of the sound tube 20^a supporting the connected discharge end of a telephone receiver 17 containing the usual diaphragm 24 and operating mechanism. At the rear of the cabinet member 21 is a door 30 whereby easy access to the enclosed parts is provided.

The receiver 17, as shown in Fig. 3, consists of an outer casing 18 which has screwed upon the upper end a cap 32 so formed as to receive the casing 18 by a screw joint or similar connection. The cap is formed with an opening at the top, and is spaced from the diaphragm 24. The vertical tapered sound tube 20^a is formed to closely contact with the cap and by means of bolts 29 disposed about the edges of the sound tube the cap is fastened thereto and maintains the casing 17 and connected parts in position. Within the space between the cap 32 and the casing 17 an inner casing 19 is disposed which contains within itself the end of the magnet well known in such receivers. The diaphragm and the outer end of the magnet are disposed so that the diaphragm ordinarily does not contact with the end of the magnet. The peripheral portions of the diaphragm are closely seated upon the contacting portions of the casing 19. To avoid

the detrimental effect of working the diaphragm against the cushioning action of a closed air pocket and the incident unequal resistance to movement I have provided the inner and outer casings 19 and 18 respectively 70 with openings so that no air pocket shall be below the diaphragm. Four of such openings are shown in the drawings and are denoted by 18^a which are in the outer casing and 19^a which are in the inner casing. By 75 this construction I have made it possible for the diaphragm 24 to act against equal resistance on each of its sides, namely, that of the atmosphere.

The casing 17 except as referred to above 80 has the regular form used in telephone receivers and has attached thereto the wires 17^a which convey the current to and from the magnet to function the diaphragm when the impulses are present in the circuit.

The circuit which conducts the impulses to the receiver 17 and its diaphragm 24 consists of wiring and apparatus as follows:

The wires 17^a run to the induction coil 14 of usual fabrication. A wire 17^b leads from said coil 14 to several cells 15 conveniently located in the bottom of the cabinet member 21 as sources of electric energy, and a wire 17^c connects the coil 14 to the transmitter 13 later described in detail. From the transmitter 13 the wire 17^d leads to the resistance switch 16 and thence to the battery 15. This switch possesses the characteristics of resistance switches as now used where the position of the swinging member thereof varies the amount of resistance interposed in the circuit and thus with the variation of the position of the swinging member the effective amount of current in the circuit may be altered as desired.

In Fig. 2 are shown the transmitter 13 and its connections to and with the tone arm 3 of the talking machine. The receiver has a screw joint with a member 11 which is fastened by soldering or some other effective means to the plug 8 which is a part of a very well known form of tone arm construction. The plug 8 ordinarily forms the end of the bent portion 4 or goose neck of a tone arm and turns with it as part 4 is moved toward and from a sound record. At 9 there is a screw connection between plug 8 and the inner sleeve portion 5 of the goose neck 4 which is of cylindrical formation and fits within the outer sleeve 6 on the end of the tone arm proper 3, which is at right angles thereto. At 7 is formed an enlargement or shoulder upon the gooseneck 4. The plug 8, outside of the inner sleeve 5, is also provided with a shoulder 10, similar to the shoulder 7, both being of the same exterior diameter as the outer sleeve 6. By reason of the two shoulders at each end of the inner sleeve 5 the gooseneck and the parts carried thereby in-

cluding the sound box oscillate in vertical planes to and from the sound record 31.

In Fig. 4, is shown a section through the plug 8, taken on the plane 4—4 of Fig. 2.

5 On the outside is seen the sleeve 6, next the sleeve 5 of gooseneck 4, and at the inside the plug 8 with six apertures 12 therethrough. Some of the sound waves passing through the gooseneck 4 to tone arm proper 3 will 10 pass through the apertures 12 and impinge upon and actuate the diaphragm 28 of the transmitter 13.

The apertures 12 are so arranged and are of such size and number, as to soften or reduce the intensity of the vibrations received 15 from the conduit 4 whereby such vibrations may act with modified force best suited to the limits of motion of a microphone diaphragm such as 28 in a telephonic circuit.

20 By the construction and arrangement of parts above set forth the sound vibrations of the reproduced sounds are transmitted to the diaphragm 28 and to the telephonic circuit leading to the receiver 17 without affecting or modifying in the slightest manner 25 the normally free action of the diaphragm or stylus bar of the sound box 2.

The operation of the device is as follows: 30 A sound record 31 is placed upon the turntable 23 of the motor mechanism and the turntable caused to rotate; the sound box 2 with stylus positioned therein is placed upon the record and the recorded sounds are thereby reproduced and conducted through 35 the conduit 4 to the tone arm 3, through the sound conduit member 25 to the continuation 25^a thereof and to the amplifier 21^a. After amplification the reproduced sound 40 may pass to the atmosphere as usual. The apparatus described is of course a well known form of sound reproducing apparatus and has to do with the development of the primary vibrations.

The secondary vibrations are those which 45 result from the transmission of the aforesaid primary sound waves from the conduit 4, through the plug 8 to the microphone diaphragm 28 of the transmitter 13. The switch 16 is manually thrown to close the 50 electric circuit whenever it is desired to supplement the primary vibrations with the secondary vibrations.

With current in the telephonic circuit the 55 vibrations of the diaphragm 28 of the microphone 13 are transformed through the action of the microphone into impulses in the electric circuit which are transmitted to the magnet of the receiver 17.

Through the action of the magnet 33 and 60 the diaphragm 24 in 17 the electric impulses are again changed the sound vibrations which, proceeding from the upper side of the diaphragm 24 pass to the tapered sound conduit 20^a and from thence to the amplifier 20. The co-acting amplifier adjacent

to amplifier 20 is seen to be capable of transmitting vibrations similar to the amplifier 20 and these vibrations of the amplifiers which are enclosed in the same cabinet pass therefrom to the atmosphere. 70

By varying the current strength through the switch control the amplitude of the secondary vibrations is or may be modified and of course by the breaking of the circuit by the switch the production of secondary 75 sound vibrations may be entirely stopped.

By suitably manipulating the apparatus to produce or not produce secondary vibrations in conjunction with the primary vibrations of sound at least three desirable and 80 advantageous results are produced; the first of which is that by cutting out the secondary vibrations a talking machine may be operated in the usual manner; secondly, when the apparatus is to be used for a larger 85 room or when greater volume is essential, the introduction of the secondary vibrations, in conjunction with the primary vibrations, supplies the needed volume with a range of regulation such as may adapt the machine, 90

first used essentially for reproduction in a small space, to one capable of filling a large room and capable of being heard over extraneous noises such as those produced by the motion of dancers and by conversation; 95 and thirdly, the advantage of having both amplifiers present in the same cabinet so that the sound produced by both may be received generally speaking as one set of sound vibrations so that the sound coming 100 simultaneously from both amplifiers to a listener appears to him to be but one sound coming from one source and having pleasing and desirable qualities or properties all of which cannot be obtained by the use of 105 either type of amplifier alone. This is so on account of the following reasons: The secondary sound vibrations produced by the telephonic circuit have tonal characteristics 110

which are peculiar thereto and quite different from those of the mechanically reproduced sounds; and it has been observed that as the volume of such electrically produced sound is increased these peculiar characteristics are augmented and emphasized so that alone and in great volume telephonically produced sounds may be objectionable from an artistic standpoint although entirely satisfactory when merely increased penetration or loudness is alone desired. With my invention, however, a double volume of reproduced sound may be easily obtained without forcing either kind of amplification and without making it necessary to emphasize or exaggerate the undesirable characteristics of either type of amplification, so that the loud amplified sound produced by my apparatus, above described, will have in it all the pleasing qualities of both types of sound amplification, free from those unde- 115 120 125 130

sirable qualities usually present in the reproduction of sound of great volume

Having thus described my invention, I claim and desire to protect by Letters Patent of the United States:

1. In a sound reproducing machine, the combination with reproducing means adapted to produce primary sound vibrations from a record tablet and a swinging tubular arm carrying said reproducer and operating as a direct conduit therefrom for said vibrations, of means to cause said primary vibrations to produce therefrom tonal vibrations secondary in character, said means including a telephonic transmitter mounted on said swinging tubular arm, whereby the diaphragm of the transmitter is actuated by said primary vibrations on their passage through said tubular arm, an electric circuit, a telephonic receiver, and an amplifying chamber into which said receiver discharges, and means thereon for deflecting the amplified sound.
2. In a sound reproducing machine, the combination with reproducing means adapted to produce primary vibrations from a record tablet, and a conduit for such vibrations, of a telephonic circuit whose transmitter is mounted on said conduit and out of contact with the sound box and stylus of the reproducer, and whose diaphragm is actuated solely by said primary vibrations, an amplifying chamber into which said conduit discharges the primary vibrations, a second amplifying chamber operatively communicating with the receiver of the telephonic circuit, a cabinet for said amplifying chambers, and means thereon for commingling and deflecting the amplified primary and secondary sound vibrations.

3. In a sound reproducing machine, the combination with means adapted to produce primary vibrations from a record tablet, and a conduit for such vibrations, of a telephonic circuit whose transmitter is mounted on said conduit and out of contact with the sound box and stylus of the reproducer, and whose diaphragm is actuated solely by said primary vibrations, an amplifier into which said conduit discharges the primary vibrations, a second amplifier operatively communicating with the receiver of the telephonic circuit, a cabinet containing both of said amplifiers, and means mounted on said cabinet and projecting over both amplifiers for directing the sound waves from said amplifiers in a common direction.

4. In a sound reproducing machine, the combination with means to produce primary vibrations from a record tablet, and a conduit for such vibrations, of a telephonic circuit whose transmitter is mounted on said conduit and out of contact with the sound box and stylus of the reproducer, and whose diaphragm is actuated solely by said pri-

mary vibrations; an amplifier into which said conduit discharges the primary vibrations, a second amplifier operatively communicating with the receiver of the telephonic circuit, a containing casing in which 70 said amplifiers are mounted adjacent to each other, and a hinged lid on said cabinet adapted to cause a commingling of said primary and secondary vibrations.

5. In a sound reproducing machine, the 75 combination with a reproducer adapted to create primary vibrations from a record tablet, and a tubular movable conduit on which the reproducer is mounted, of a telephonic circuit whose transmitter is mounted on said 80 conduit and out of contact with the reproducer, and whose diaphragm is actuated solely by said primary vibrations, an amplifier operatively communicating with the receiver of the telephonic circuit, a resistance 85 switch controlling said circuit, and an adjustably pivoted member cooperating with the resistance switch to vary the volume of the amplified sound.

6. In a sound reproducing apparatus, 90 means to reproduce recorded sound vibrations from a rotatable tablet, comprising a sound box and stylus, a conduit for said sound vibrations, amplifying means into and through which said sound vibrations 95 are discharged, a branch conduit from the conduit receiving said sound vibrations, a microphone connected to said branch conduit, an electric circuit, a receiver therein, a sound conduit from the receiver, an amplifying member communicating with the last mentioned sound conduit, and means to direct and commingle the amplified sound waves issuing from both of said amplifiers.

7. In a sound reproducing apparatus, a reproducer, a conduit for sound vibrations created thereby, said conduit having a threaded flanged opening, a telephonic circuit whose transmitter is actuated solely by said sound vibrations, a perforated plug 110 which is threaded and adapted to register with the threaded opening of said conduit, and a transmitter mounted on the opposite end of said plug.

8. In a sound reproducing machine, the 115 combination with sound reproducing means for producing primary sound vibrations from a sound record, a conduit for said primary vibrations, a telephonic circuit including a transmitter communicating with said conduit and adapted to be actuated by said primary vibrations, and a receiver for producing secondary sound vibrations arranged to discharge and commingle the same with said primary sound vibrations thereby joining the primary vibrations and supplementing the same by volume and other characteristics.

9. In a sound reproducing machine, the 130 combination with sound reproducing means

for producing sound vibrations from a sound record, a conduit for said primary vibrations, a telephonic circuit including a transmitter communicating with said conduit and adapted to be actuated by said primary vibrations, and a receiver for producing secondary sound vibrations and arranged to discharge the same simultaneously with the discharge of the primary vibrations, the transmitting and discharging means being positioned within the same enclosing cabinet.

10. In a sound reproducing machine, the combination with sound reproducing means for producing primary sound vibrations from a sound record, said primary vibrations being mechanically reproduced, a conduit for said primary vibrations, and a telephonic circuit including a transmitter communicating with said conduit and adapted to be actuated by said primary mechanical vibrations, a receiver for producing secondary sound vibrations and an amplifier therefor, an amplifier for the primary vibrations, and means whereby the combined vibrations shall be discharged from the same integral machine.

11. The combination with a talking machine, of electrical means actuated by and without substantially detracting from the sound mechanically produced by the operation of said machine from a record thereon, to substantially augment to a listener to a reproduction of sound from said machine the volume of sound produced by said machine.

12. The combination with a talking machine, of electrical means mounted therein and actuated by the sound waves produced during the reproduction of sound by said machine from a record thereon to substantially augment to a listener the volume of sound emitted from said machine, and means to vary at will the extent to which said

15. volume is so augmented.

13. The combination with a talking ma-

chine cabinet and a talking machine mounted therein, of electrical means also mounted within said cabinet and actuated by the sound produced by said machine during the 50 mechanical reproduction of sound thereby to substantially augment to a listener to said machine the volume of sound emitted therefrom.

14. The combination with a talking machine cabinet and a talking machine enclosed therein, of telephonic means mounted within said cabinet and actuated by the sound produced by said machine during the 55 reproduction of sound thereby, to substantially augment to a listener to said machine the volume of sound emitted from said machine.

15. The combination with a talking machine cabinet and a talking machine mounted therein, of electrical means mounted within said cabinet and actuated by the sound produced by said machine during the reproduction of sound thereby, to substantially augment to a listener to said machine 60 the volume of sound emitted from said machine, and means to vary the extent to which the said volume is so augmented.

16. The combination with a talking machine cabinet and a talking machine mounted therein, of telephonic means arranged to be thrown into and out of operation at will mounted within said cabinet and when thrown into operation actuated by the sound produced by said machine during the reproduction of sound thereby, to augment to a listener to the reproduction of sound from said machine the volume of sound emitted by said machine.

In witness wherof, I have hereunto set my 85 hand and seal this 15 day of April, A. D., 1916.
